Reuben Hood. Fish. New York
Letters Patent.

The Schedule referred to in these Letters Patent and making part of the same containing a description in the words of the said Reuben Hood himself of his improvement in the composition of matter for curing several kinds evil and moist kinds of old sores.

To all to whom these presents shall come. To be it known that I Reuben Hood of Fish in the County of Bronx and State of New York have discovered and invented a new and useful manner of composition of matter called "Aash for curing several kinds sores, blisters, evil and moist kinds of old sores" and that the following is a full and exact description of the said invention or composition of matter, and the manner in which it should be used to wit. Take 2 1/2 drams of blue vitriol. 4 drams of alum. 6 drams of loaf sugar dissolve them in one pint of good vinegar. add three table-spoonsful of honey and the mixture is fit for use. Wrap the sore clean and wash it twice a day with the above mixture until completely healed. The sore should be covered with a soft plaster or cloth to keep the air from it and to keep it moist. If the patient cannot bear a wash of the strength stated it must be diluted with water until it can be borne without great pain. The strength must be graduated according to the sensibility of the patient and the pain which arises always bearing in mind that it should be weak if a great strength as the patient can bear. The wash thus used will effect a complete cure of the most obdurate cases of jive sore and blisters, evil and generally within the period of from one to six months. It is also equal with great success for old and chronic sores, scrofula, sore eyes &c. I claim to have discovered that a combination of the above ingredients in the proportion indicated in the manner stated and the application of the mixture as
